[57] **CLAIM**

The ornamental design for a combined control unit for input and output of information and word processor, as shown and described.

DESCRIPTION

FIG. 1 is a top, front and right side perspective view of a combined control unit for input and output of information and word processor according to our new design;
 FIG. 2 is a front elevational view thereof;
 FIG. 3 is a rear elevational view thereof;
 FIG. 4 is a top plan view thereof;
 FIG. 5 is an enlarged sectional view thereof taken at line 5—5 in FIG. 4;
 FIG. 6 is a right side elevational view thereof;
 FIG. 7 is a left side elevational view thereof;
 FIG. 8 is a bottom plan view thereof;
 FIG. 9 is a front elevational view thereof in closed position;
 FIG. 10 is a right side elevational view thereof in closed position; and,
 FIG. 11 is a top plan view thereof in closed position.
